UNITED STATES PATENT OFFICE.

WILLIAM G. HAWLEY, OF ELMIRA, NEW YORK, ASSIGNOR TO AMERICAN LA FRANCE FIRE ENGINE COMPANY, INC., OF ELMIRA, NEW YORK, A CORPORATION OF NEW YORK.

ROTARY PUMP.

1,129,091.

Specification of Letters Patent. Patented Feb. 23, 1915.

Application filed April 8, 1914. Serial No. 830,476.

To all whom it may concern:

Be it known that I, WILLIAM G. HAWLEY, a citizen of the United States, and resident of Elmira, county of Chemung, and State of New York, have invented certain new and useful Improvements in Rotary Pumps, of which the following is a full and clear specification.

This invention relates to rotary pumps, its primary object being to provide an improved construction for a pump of this character by virtue of which the flow of fluid (such for example as water in fire engine pumps) will be facilitated and gradually accelerated.

One of the objects of the present invention is to simplify the construction of the pump housing by making it in few parts and providing securing means which at the same time serve to bring the parts into proper register with each other prior to being fastened.

Other and more specific objects will appear in the claims, reference being had to the accompanying drawings which exemplify my invention in its application to a fire engine pump.

In the drawings, Figure 1 is a side elevation of one embodiment of my invention; Fig. 2 is a top plan view of the same; Fig. 3 is an end elevation of the same; Fig. 4 is a section on the line IV—IV, Fig. 1; Fig. 5 is a side elevation similar to Fig. 1 with the nearer side wall portion removed; Fig. 6 is a similar side elevation with the gears removed.

In the present application, the specific shape of the bridges which separate the suction and pressure chambers adjacent the plane of the axes of the rotary pump elements is not claimed, such construction being shown and described in my co-pending application, Serial Number 830,475 of even date. The same may be said of the form of the interdental space in relation to the bridges.

As shown in the drawing the present embodiment of my invention contemplates more especially an improved housing construction for rotary pumping elements 1 and 2, provided with portions 3 which intermesh. Said rotary pumping elements are preferably intermeshing gears, one of which serves to drive the other. In the present instance, 2 is the driving gear, keyed to the

shaft 4 which as shown in Fig. 2, extends beyond the wall of the housing and is provided with a keyway slot 5 adapted to receive a suitable gear or pulley for driving the same. As shown in the several views, 60 the housing comprises a central shell 6 which, as shown in Figs. 5 and 6, provides a suction chamber 7 and a pressure chamber 8, the walls of said shell being conformed to the peripheries of the gears 1 and 2. The bottom wall 9 of the shell 6 is sloped downwardly from the ends toward the center of the suction chamber 7 to form a depression 10 on either side of an inwardly protruding boss 11 which extends throughout the wall of the shell and is provided with a hole 12 which is reamed to provide a finished bearing surface so that the bolt which is also provided with a finished outer surface to fit the hole 12, is adapted when inserted therein to accurately determine the position of the side wall portions of the housing with respect to the central shell. Said wall 6 is of substantially the same width as the gears 1 and 2 and is provided 80 on its opposite lateral faces with flanges 13, having spaced holes 14 for suitable bolts or other fastenings which serve to secure the side wall portions thereto. The upper wall of the shell 6 is also provided with 85 reamed holes 15 similar to the hole 12 and for the same purpose. A fluid conveying gallery 16 surmounts the shell 6 and is provided with branches 17 extending toward opposite ends of the housing. Pressure 90 chamber 8 opens into the gallery 16.

Referring more especially to Figs. 3 and 4, it will be noted that each of the side wall portions are provided with attaching flanges 18 which are secured to the flanges 13 of the central shell 6. Furthermore, it will be noted that each of the side wall portions are provided with recesses 19 below the plane of the axes of rotation of said pump elements, said recesses conforming in general 95 contour with the suction chamber 7 and in effect making such suction chamber of considerably greater width than said pumping elements. Suitable bearings 20 for the pumping elements are provided in the side 100 wall portions, and as shown in Fig. 4, overhang the recesses 19. Each of the side wall portions is provided with partitions 21 extending inwardly toward the suction chamber 7 and terminating under the bearings 20. 110

Said partitions 21 form between them and the outer walls of the housing, conveying channels 22 which lead in pairs from the inlet shells 23 at either end of the housing. Each 5 of the inlet shells 23 comprises branches 24 which communicate respectively with the channels 22. As shown by dotted lines in Fig. 2, the outer walls of the channels 21 are deflected inwardly at 25 for the purpose 10 of deflecting the incoming fluid toward the rotary pumping elements. Preferably I construct each of the inlet shells 23 in the form of a Y-shaped casting provided with a flange 26 which may be secured to the flanges 27 at either end of the housing. Above the plane of the rotary axes, the side wall portions are provided with recesses 28 which constitute extensions to the pressure 15 chamber 8 and make such pressure chamber in effect of greater width than the rotary gears 1 and 2. In order, however, to gradually restrict the fluid to the dimensions of the gallery 16 the width of the pressure chamber, as shown in Fig. 4, is less than 20 the width of the suction chamber 19. Above the plane of axes each of the side wall portions is provided with a flat wall 29 which extends inwardly toward the pressure chamber 8, and is in substantial contact with the 25 side faces of the gears 1 and 2 in their travel above said plane. Extending between the flat surfaces 29 and on the same level therewith is the bridge 30 in each side wall portion, said bridges serving to prevent the flow 30 of water from the pressure chamber back to the suction chamber.

Referring now to Figs. 1, 3 and 4, it will be seen that a plurality of stiffening ribs 31 are provided on the outer walls of the 35 side wall portions, said ribs preferably forming a V opening upwardly and extending across the suction and pressure chambers. The legs of the V are preferably approximately tangent to the bearings 20 of the rotary pumping elements, being thereby afforded material support and at the same time serving to stiffen said bearings. Preferably, the bosses which contain the reamed 40 holes 12 and 15 are disposed at the apex 45 and upper ends of the ribs 31 respectively. The bolts 32 which extend through the holes 12 and 14 and serve to hold the side wall portions to the central shell 6 are finished to fit exactly the holes 12 and 15, being there- 50 by adapted to serve as dowels for locating the side wall portions with respect to the central shell 6. As shown in Fig. 3 a corner 33 in each of the inlets 23 serves to divide the inflowing current into the respective branches 24 leading to the channels 22.

I claim:

1. In a rotary pump, a pump housing provided with suction and delivery chambers, a rotary pumping element which 65 forces fluid from said suction chamber into

said delivery chamber, and means for supplying fluid to said suction chamber through the opposite lateral walls of said pump housing, said rotary pumping element being rotatable on an axis extending transversely to said lateral walls, said pump element being provided with oppositely disposed bearings, the walls of which are exposed to the cooling effects of the fluid entering from the opposite sides respectively. 70 75

2. In a pump, a pair of pumping elements rotatable about parallel axes, said pumping elements having intermeshing portions, a housing for said pumping elements provided with suction and delivery chambers 80 respectively on opposite sides of the line of centers of rotation of said pumping elements, said suction chamber being provided with a recess extending laterally from one side of said pumping elements and in open 85 communication therewith, and a suction pipe for supplying fluid to said recess.

3. In a pump, a pair of pumping elements rotatable about parallel axes, said pumping elements having intermeshing portions, 90 a housing for said pumping elements provided with suction and delivery chambers disposed respectively on opposite sides of the line of centers of said rotary pumping elements, said suction chamber being provided with recesses extending laterally from both sides of said pumping elements, and a suction pipe provided with branches leading 95 to said recesses respectively.

4. In a pump having rotary pumping elements provided with intermeshing portions, the spaces between said portions constituting fluid conveying chambers, a housing for said pumping elements provided with suction and delivery chambers, said suction chamber 100 being of greater width than said pumping elements and a suction pipe provided with branches communicating with said suction chamber from opposite sides thereof. 105

5. In a pump, a pair of rotary intermeshing pumping elements, a housing therefor having suction and pressure chambers of greater width than said pumping elements, said housing being provided with walls adjacent the lateral faces of said pumping elements and with inlet passages for fluid arranged outside said walls and communicating respectively with opposite sides of said suction chamber. 110 115

6. In a pump, a pair of rotary intermeshing pumping elements, a housing therefor having suction and pressure chambers of greater width than said pumping elements, said housing being provided with walls adjacent the lateral faces of said pumping elements and with inlet passages for fluid arranged outside said walls and communicating respectively with opposite sides of said suction chamber, and a common inlet pipe for said passages. 120 125 130

7. In a pump, a pair of rotary intermeshing pumping elements, a housing therefor having suction and pressure chambers of greater width than said pumping elements, 5 said housing being provided with walls adjacent the lateral faces of said pumping elements and with inlet passages for fluid arranged outside said walls and communicating respectively with opposite sides of said 10 suction chamber, and a common inlet pipe for said passages, arranged at each end of said housing.

8. In a pump, intermeshing pumping elements rotatable on parallel axes, a housing 15 for said pumping elements providing suction and pressure chambers respectively on opposite sides of the plane of said axes, the side walls of said suction chamber being spaced from the lateral faces of said pumping elements, said suction chamber being provided with partitions adjacent the side 20 faces of said pumping elements, said partitions forming inlet passages extending from one end of the pump housing along 25 the side faces of said pumping elements, and means for conveying fluid to said passages.

9. In a pump, intermeshing pumping elements rotatable on parallel axes, a housing for said elements providing suction and pressure chambers on opposite sides of the plane 30 of said axes, said housing being provided with inner walls in substantial contact with the walls of said elements and extending from said pressure chamber to adjacent to 35 said plane, the lateral walls of said suction chamber being spaced from said elements, partitions arranged within said suction chamber between said pumping elements and the lateral walls of the suction chamber to 40 provide fluid channels parallel to the side walls of said pumping elements, and an inlet provided with branches respectively communicating with said channels.

10. In a pump, intermeshing pumping elements rotatable on parallel axes, a housing 45 for said elements providing suction and pressure chambers on opposite sides of the plane of said axes, said housing being provided with inner walls in substantial contact with the walls of said elements and extending from said pressure chamber to adjacent to 50 said plane, the lateral walls of said suction chamber being spaced from said elements, partitions arranged within said suction chamber between said pumping elements and the lateral walls of the suction chamber to 55 provide fluid channels parallel to the side walls of said pumping elements, and an inlet provided with branches respectively communicating with said channels, said partitions being arranged to extend from adjacent to a vertical plane parallel to and intermediate of said axes and toward opposite 60 ends of said housing.

65 11. In a pump, intermeshing pumping

elements rotatable on parallel axes, a housing for said elements providing suction and pressure chambers on opposite sides of the plane of said axes, said housing being provided with inner walls in substantial contact 70 with the walls of said elements and extending from said pressure chamber to adjacent to said plane, the lateral walls of said suction chamber being spaced from said elements, partitions arranged within said suction chamber between said pumping elements and the lateral walls of the suction chamber to provide fluid channels parallel to the side walls of said pumping elements, and an inlet provided with branches respectively 80 communicating with said channels, said partitions being arranged to extend from adjacent to a vertical plane parallel to and intermediate of said axes and toward opposite 85 ends of said housing, the inner walls of said partitions being spaced farther apart than said contacting walls.

12. In a pump, intermeshing pumping elements rotatable on parallel axes, a housing for said elements provided with suction and pressure chambers respectively disposed on opposite sides of the plane of said axes, said suction chamber being of greater width than said elements and said housing being provided with inlet channels extending 90 from said suction chamber toward one end of said housing and outside of said pumping elements.

13. In a pump, intermeshing pumping elements rotatable on parallel axes, a housing 100 for said elements provided with suction and pressure chambers respectively disposed on opposite sides of the plane of said axes, said suction chamber being of greater width than said elements, and said housing being provided with inlet channels extending from said suction chamber toward one end of said 105 housing and outside of said pumping elements, said channels being arranged intermediately of said plane and a plane tangent to the peripheries of said pumping elements.

14. In a pump, intermeshing pumping elements rotatable on parallel axes, a housing for said elements provided with suction and pressure chambers respectively disposed on opposite sides of the plane of said axes, said suction chamber being of greater width than said elements and said housing being provided with inlet channels extending from said suction chamber toward one end of 115 said housing and outside of said pumping elements, said channels being arranged intermediately of said plane and a plane tangent to the peripheries of said pumping elements, the inner walls of said housing adjacent the inner ends of said channels being deflected inwardly.

15. In a pump, intermeshing pumping elements rotatable about parallel axes, a housing for said elements of greater width than 120

- 5 said elements, said housing providing suction and pressure chambers extending across its entire width, said chambers being arranged on opposite sides of the plane of said axes, said housing being provided with walls in contact with said elements and extending from said pressure chamber in opposite directions toward said plane inlets at opposite ends of said housing, and partitions 10 arranged in said suction chamber adjacent the lateral faces of said pumping elements to provide channels extending from said inlets toward that portion of the suction chamber lying beneath the intermeshing portions of said pumping elements.
- 15 16. In a pump, intermeshing pumping elements rotatable about parallel axes, a housing for said elements of greater width than said elements, said housing providing suction and pressure chambers extending across its entire width, said chambers being arranged on opposite sides of the plane of said axes, said housing being provided with walls in contact with said elements and extending from said pressure chamber in opposite directions toward said plane, inlets at opposite ends of said housing, and partitions 20 arranged in said suction chamber adjacent the lateral faces of said pumping elements to provide channels extending from said inlets toward that portion of the suction chamber lying beneath the intermeshing portions of said pumping elements, said partitions being arranged on both sides of the pumping elements and said inlets having forked branches communicating respectively with the channels formed by said partitions, said suction chamber being provided with a central depression and said inlets being arranged adjacent said plane, said channels being inclined downwardly toward said central depression, and the outer walls of said channels being deflected inwardly toward said central depression.
- 25 17. In a pump, intermeshing pumping elements rotatable about parallel axes, a housing for said elements of greater width than said elements, said housing providing suction and pressure chambers extending across its entire width, said chambers being arranged on opposite sides of the plane of said axes, said housing being provided with walls in contact with said elements and extending from said pressure chamber in opposite directions toward said plane, inlets at opposite ends of said housing, and partitions 30 arranged in said suction chamber adjacent the lateral faces of said pumping elements to provide channels extending from said inlets toward that portion of the suction chamber lying beneath the intermeshing portions of said pumping elements, said partitions being arranged on both sides of the pumping elements and said inlets having forked branches communicating respectively with the channels formed by said partitions.
- 35 18. In a pump, intermeshing pumping elements rotatable about parallel axes, a housing for said elements of greater width than said elements, said housing providing suction and pressure chambers extending across its entire width, said chambers being arranged on opposite sides of the plane of said axes, said housing being provided with walls in contact with said elements and extending from said pressure chamber in opposite directions toward said plane, inlets at opposite ends of said housing, and partitions 40 arranged in said suction chamber adjacent the lateral faces of said pumping elements to provide channels extending from said inlets toward that portion of the suction chamber lying beneath the intermeshing portions of said pumping elements, said partitions being arranged on both sides of the pumping elements and said inlets having forked branches communicating respectively with the channels formed by said partitions, said suction chamber being provided with a central depression and said inlets being arranged adjacent said plane, said channels being inclined downwardly toward said central depression, and the outer walls of said channels being deflected inwardly toward said central depression.
- 45 19. In a pump, intermeshing pumping elements rotatable about parallel axes, a housing for said elements of greater width than said elements, said housing providing suction and pressure chambers extending across its entire width, said chambers being arranged on opposite sides of the plane of said axes, said housing being provided with walls in contact with said elements and extending from said pressure chamber in opposite directions toward said plane, inlets at opposite ends of said housing, and partitions 50 arranged in said suction chamber adjacent the lateral faces of said pumping elements to provide channels extending from said inlets toward that portion of the suction chamber lying beneath the intermeshing portions of said pumping elements, said partitions being arranged on both sides of the pumping elements and said inlets having forked branches communicating respectively with the channels formed by said partitions, said pumping elements being provided with journals and bearings therefor, the walls of said bearings constituting portions of the walls of said channels to cool said bearings.
- 55 20. In a pump, intermeshing gears which constitute the pumping elements, said gears being rotatable about parallel horizontal axes, a housing for said gears providing a suction chamber below the plane of said gears and a pressure chamber above said plane, said suction chamber being of greater width than said gears and having inlets leading from opposite ends of said housing adjacent the side walls of said gears, said 60 65 120 125 130

- 5 pressure chamber being of greater width than said gears to permit the discharge of fluid laterally from the chambers formed between intermeshing teeth but of less width than said suction chamber to provide a graded reduction in space for elevating the pressure in said pressure chamber, the lateral walls of said housing being provided with bridges separating said chambers.
- 10 21. In a pump, the combination with intermeshing gears constituting the pumping elements, said gears being rotatable about parallel axes, of a housing for said rotary pumping elements comprising a central shell of substantially the same width and conforming to the peripheries of said gears and providing suction and pressure chambers on opposite sides of the plane of said axes, side wall portions for closing the sides of said central shell, said shell and side wall portions being provided with bolt holes having finished bearing walls, and bolts extending through said holes and having finished surfaces, contacting with the finished walls of said holes to positively hold said side wall portions in accurate register with said central shell.
- 15 22. In a pump, the combination with intermeshing gears constituting the pumping elements, said gears being rotatable about parallel axes, of a housing for said rotary pumping elements comprising a central shell of substantially the same width and conforming to the peripheries of said gears and providing suction and pressure chambers on opposite sides of the plane of said gears, side wall portions for closing the sides of said central shell, said shell and side wall portions being provided with bolt holes having finished bearing walls, and bolts extending through said holes and having finished surfaces contacting with the finished walls of said holes to positively hold said side wall portions in accurate register with said central shell, said side wall portions being provided with reinforcing ribs extending from the bolt holes above said plane of the axes to the bolt holes below said plane.
- 20 23. In a pump, the combination with intermeshing gears constituting the pumping elements, said gears being rotatable about parallel axes, of a housing for said rotary pumping elements comprising a central shell of substantially the same width and conforming to the peripheries of said gears and providing suction and pressure chambers on opposite sides of the plane of said gears, side wall portions for closing the sides of said central shell, said shell and side wall portions being provided with bolt holes having finished bearing walls, and bolts extending through said holes and having finished surfaces contacting with the finished walls of said holes to positively hold said side wall portions in accurate register with said central shell, said side wall portions being provided with depressions registering with and forming extensions to said suction and pressure chambers.
- 25 24. In a pump, the combination with intermeshing gears constituting the pumping elements, said gears being rotatable about parallel axes, of a housing for said rotary pumping elements comprising a central shell of substantially the same width and conforming to the peripheries of said gears and providing suction and pressure chambers on opposite sides of the plane of said axes, side wall portions for closing the sides of said central shell, said shell and side wall portions being provided with bolt holes having finished bearing walls, and bolts extending through said holes and having finished surfaces contacting with the finished walls of said holes to positively hold said side wall portions in accurate register with said central shell, said side wall portions being provided with reinforcing ribs extending from the bolt holes above said plane of the axes to the bolt holes below said plane.
- 30 25. In a pump, the combination with intermeshing gears constituting the pumping elements, said gears being rotatable about parallel axes, of a housing for said rotary pumping elements comprising a central shell of substantially the same width and conforming to the peripheries of said gears and providing suction and pressure chambers on opposite sides of the plane of said axes, side wall portions for closing the sides of said central shell, said shell and side wall portions being provided with bolt holes having finished bearing walls, and bolts extending through said holes and having finished surfaces contacting with the finished walls of said holes to positively hold said side wall portions in accurate register with said central shell, said side wall portions being provided with bearings for said rotary pumping elements and with stiffening ribs extending from said bearings across the lateral walls of said suction and pressure chambers.
- 35 26. In a pump, the combination with intermeshing gears constituting the pumping elements, said gears being rotatable about parallel axes, of a housing for said rotary pumping elements comprising a central shell of substantially the same width and conforming to the peripheries of said gears and providing suction and pressure chambers on opposite sides of the plane of said axes, side wall portions for closing the sides of said central shell, said shell and side wall portions being provided with bolt holes having finished bearing walls, and bolts extending through said holes and having finished surfaces contacting with the finished walls of

said holes to positively hold said side wall portions in accurate register with said central shell, said side wall portions being provided with bearings for said rotary pumping elements and with stiffening ribs extending from said bearings across the lateral walls of said suction and pressure chambers, said ribs forming a substantially V-

shaped enlargement on each of said side wall portions, the open end of the V being 10 arranged on the outer wall of the pressure chamber.
